UNITED STATES PATENT OFFICE.

THOMAS C. JOYCE, OF BERLIN, WISCONSIN.

COMMODE.

SPECIFICATION forming part of Letters Patent No. 409,590, dated August 20, 1889.

Application filed April 25, 1889. Serial No. 308,514. (No model.)

To all whom it may concern:

Be it known that I, THOMAS C. JOYCE, a citizen of the United States, residing at Berlin, in the county of Green Lake and State of Wisconsin, have invented certain new and useful Improvements in Commodes, of which the following is a specification, reference being had therein to the accompanying drawings, in which—

10 Figure 1 represents a perspective view of my improved commode, showing the top or lid thrown back and the arms locked in place ready for use; Fig. 2, a vertical sectional view of the commode closed; Fig. 3, a similar view 15 taken at right angles to the line on which Fig. 2 is taken; Fig. 4, a detail sectional view of the removable draw adapted to contain the vessel or pot and confine the odors arising therefrom; and Fig. 5, a detail sectional view 20 of one of the curved hinged arms, showing the spring-catch.

This invention has particular reference to invalids' and children's commodes of that class wherein all the parts are contained 25 within a casing mounted upon suitable supporting-legs; and it consists in certain novel features of construction and combination of parts, that will be fully hereinafter specified, and particularly pointed out in the claims 30 appended.

The essential object I have in view is to provide improved and simple means whereby when the draw is removed from the commode-casing to be carried out of the apartment an 35 automatic flexible cover will close over the opening of the draw, and thereby prevent the escape and dissemination of disagreeable and unhealthful odors into the apartment, as will be more fully hereinafter specified.

40 The invention also has other minor objects in view, which will fully appear in the course of this description.

Referring to the annexed drawings, A designates a suitable casing or box, of substantially a rectangular shape, which is mounted 45 upon suitable supporting-legs, and is provided with a hinged lid or top which is adapted to be turned up into a vertical position, as shown in Fig. 1, to form a back or rest for the 50 occupant of the commode. A removable seat-

piece B is fitted within the casing A and rests upon cleats *a* upon the interior of said casing, the said seat being provided with the usual opening *b*. This seat B is held removably within the commode-body by means of a small 55 plate or pin *c*, which is secured to the seat and projects into a recess in the body. Inserted in the commode-body, from the rear side preferably, is a removable draw C, which is provided with a suitable handle, and is 60 guided in its movements by means of bars *d*, secured in the lower inner corners of the commode-body. This draw C is provided with a double bottom *e* and grooved side pieces *f*, as shown. Between the portions of the double 65 bottom *e* and in the grooves in the side pieces *f* is adapted to slide a flexible cover D, which is sufficiently long to extend from the forward end of the draw back around the grooves in the rear ends of the sides *f* and down 70 between the bottom portions, as shown in Fig. 4. The lower end of the folding cover is provided with a catch or lug *g*, which projects through a slot *a'* in the lower portion of the double bottom, and is adapted to engage a 75 spring-catch *h*, recessed in the bottom of the commode-body. When the draw is inserted in the commode-body, the lug *g* catches in the recess in which the spring-catch is secured, and as the draw is pushed into the 80 casing the flexible cover will be automatically drawn down between the bottom portions of the draw, uncovering the pot contained within the draw. When the draw is withdrawn from the casing, the lug *g* will automatically engage the spring-catch *h*, and the flexible cover will be thereby pushed up over the opening in the draw, entirely closing 85 the same and preventing the escape of the odors arising from the inclosed pot. 90 When the draw is drawn entirely out, the lug *g* will automatically slip off the spring-catch. The draw and hinged top are made to fit closely to their respective seats to prevent the escape of odors while the commode 95 is not in use.

To support and hold the hinged lid when thrown back, I provide a pair of arms F, each of which is secured rigidly to the lid and provided with a curved hinged section *k*. The 100

lower ends of the said curved sections are each provided with a spring-catch *l*, which are adapted to engage notched plates *m*, secured to the seat *B*, and thereby hold the arms in position. The catches *l* are provided with thumb-pieces *n*, by means of which they are disengaged from the plates on the seat *B* when it is desired to close the commode. When the lid is thrown down and the commode closed, the hinged curved sections *k* are folded over upon the main section, as shown in Figs. 2 and 3, the arms thus folded being passed down between the side edges of the seat-piece and the respective sides of the commode-body. When the arm-sections are thus folded back, the thumb-pieces *n* and eyes *p* are set in suitable recesses *r*, formed in the hinged lid and arms. A strap or guard *G* is stretched between the arm-sections and detachably secured to the eyes *p* in the arm-sections by means of spring-clasps or snap-hooks *s*. This guard is employed when the commode is occupied by young children and serves to prevent them falling off the seat. This guard is removed entirely when the commode is closed.

Having thus fully described my invention, what I claim, and desire to secure by Letters Patent, is—

1. In a commode, the combination of a casing, a lid hinged to the casing and provided with arms *F*, curved sections *k*, hinged to the ends of these arms, spring-catches upon the lower ends of these sections *k*, and a seat *B*, fitted within the casing and provided with notched plates *m*, substantially as and for the purpose herein set forth. 30

2. In a commode, the combination of a casing, a removable draw inserted in this casing, a sliding flexible cover mounted in grooves 40 upon this draw, a lug attached to this folding cover, and a spring-catch secured upon the said casing and adapted to engage the said lug, as and for the purpose set forth.

In testimony whereof I affix my signature 45 in presence of two witnesses.

THOMAS C. JOYCE.
